UNITED STATES PATENT OFFICE.

JOHN H. RICHARDSON, OF SAUGUS, MASSACHUSETTS, ASSIGNOR TO UNITED SHOE MACHINERY COMPANY, OF PATERSON, NEW JERSEY, A CORPORATION OF NEW JERSEY.

HEEL-BUILDING MACHINE.

1,148,716.

Specification of Letters Patent.

Patented Aug. 3, 1915.

Application filed October 6, 1911. Serial No. 653,090.

To all whom it may concern:

Be it known that I, JOHN H. RICHARDSON, a citizen of the United States, residing at Saugus, in the county of Essex and State 5 of Massachusetts, have invented certain Improvements in Heel-Building Machines, of which the following description, in connection with the accompanying drawings, is a specification, like reference characters on the 10 drawings indicating like parts in the several figures.

This invention relates to heel building machines, and more particularly to that type 15 of machine in which a plurality of lifts or pieces of leather are assembled and fastened together to form a heel.

Certain features of the invention, however, are not limited in their utility to use 20 in connection with a machine of the particular kind referred to, but may be embodied in many different machines for operating upon heels.

Heretofore, according to a common practice, heel lifts have been assembled manually 25 in a mold and held under pressure, while being nailed together by power operated mechanism under the manual control of the operator. In machines embodying these features the controlling devices for the nail 30 driving mechanism have not been dependent in their operation upon the thickness, or height, of the heel. In other words, the nail driving mechanism could be thrown into operation to fasten the heel lifts together 35 irrespective of the height of the heel and irrespective of uniformity between the successive heels which were built.

The object of the present invention is to 40 provide a machine which will turn out a product the uniformity of which is automatically insured, irrespective of carelessness or lack of skill on the part of the operative.

To this end a feature of the invention consists in mechanism for measuring the height 45 of the pile of lifts and preventing the operation of the nail driving mechanism if such pile is not of the proper height. A consequence of this is that, when the machine is 50 adjusted for building heels of a certain height, successive heels will all be substantially the same in height. A highly desirable uniformity in the product is thus secured, independently of the skill or care exercised by 55 the operative. The measuring mechanism

may comprise a member to be set, automatically or otherwise, in accordance with the height of the heel to be built, and having a recess with which a pin, carried by a heel engaging member, is adapted to register 60 only when the heel is of the proper height. The said pin may be so placed as to prevent operation of the devices for controlling operation of the driving mechanism when the pin is not in position to register with the 65 recess in the first mentioned member. The recess is preferably formed to permit a small amount of variation in the heights of heels, since it is often extremely difficult, if not impossible, to select lifts to form a pile 70 of exactly the height desired.

Another feature of the invention comprises an improved mold in which the lifts are assembled and which is capable of accommodating a larger variety of sizes and shapes 75 of heels than the molds previously used for this purpose. The mold consists mainly of pivoted jaws which are crossed and may be opened and closed to conform to heels of a variety of sizes and styles. The jaws are 80 preferably pivoted at points somewhat remote from where they engage the heel, in order to secure a wider range of adaptability than would otherwise be enjoyed.

In the following specification one mechanical embodiment of the invention will be specifically described for the purpose of illustration, but it should be understood that the invention is not limited in its scope to the embodiment described in detail, except 90 in so far as defined by the claims at the end of said specification.

In the drawings:—Figure 1 is a side elevation of a machine embodying the invention; Fig. 2 is a central vertical section of the machine from front to rear; Fig. 3 is a perspective view of the upper part of the machine; Fig. 4 is a detail perspective view showing the construction and mounting of the mold jaws; and Fig. 5 is a perspective 100 view showing a detail of the measuring device.

The frame of the machine is designated by the reference numeral 10 and may be of any suitable shape and construction. Pivoted 105 mounted within the frame 10 is a swinging arm 12 which is constructed to swing about the pivot pin 14 as clearly shown in Fig. 2. Mounted at the upper end of the arm 12 is a pair of handles 16. The arm 12 performs 110

the dual function of controlling the operation of the power operated mechanism of the machine and transmitting pressure to the pile of heel lifts in order to hold them securely in position while a nail or nails are being driven therethrough.

A member 18 is secured to the frame of the machine by suitable means, such as bolts 20. The upper surface of the member 18 forms the bottom of the mold in which a pile of heel lifts is assembled in the process of building a heel. A pair of crossed arms 22, 24 are mounted upon pivots 26, 28, respectively, at the rear of the member 18 in such a manner that the said arms swing or slide laterally upon the upper surface of said member. The forwardly projecting portions of the arms 22, 24 constitute the work engaging jaws or the sides of the heel mold, and are constructed to be moved toward each other to center and position the heel lifts with relation to each other.

The means for effecting movement of the side jaws is best shown in Fig. 4, and comprises the following construction:—A pin 30 is held in an arm 32 by means of a set screw 34. The arm 32 is rigid with the arm 24 and consequently moves therewith. Another arm 36 is in rigid relation to the arm 22 and is notched at its end to receive the pin 30. Inasmuch as the pivots 26, 28 are stationary, the connections just described will insure that the side jaws shall always move equally and oppositely. A cam roll 38 is carried upon the under side of the arm 32 and travels in a cam path 40 formed in an enlargement 42 upon the arm 44 of a bell crank lever 46. To the other arm 48 of the bell crank lever is pivoted a connecting rod 50 which extends downwardly to a suitable treadle or other device to be actuated by the operative, the connecting rod being normally held in its elevated position. The cam 40 is so formed that when the bell crank lever 46 is swung in a counter clockwise direction as viewed in Fig. 4, the cam roll 38 will move rearwardly; the result of this is to swing the side jaws of the heel mold toward each other through equal distances. By placing the pivots 26, 28, about which the heel-engaging jaws swing, each upon the opposite side of the mold from its respective jaw and somewhat remote therefrom, the mold is well adapted for use with heels of a large range of sizes and shapes, since the contour of the mold cavity is maintained at a close approximation to that of an average heel, while the jaws are swung through considerable distances.

The member 18 is recessed to receive a nail block or die 52, said nail block being retained in position by pivoted wings 54. A slot 56 is cut in the forward portion of the nail block, forming a guideway for a

bracket 58 to which is secured the breast member 60 of the mold. A bolt 62 passing through the slot 56 may be tightened to secure the breast member 60 in any desired position of adjustment forwardly or rearwardly. The breast member 60 is preferably secured to the bracket 58 by a screw or bolt 64 to the end that the said breast member may be easily removed and another of different height substituted therefor when desired. The occasion for this arises from the fact that the breast member of the mold is used as a gage for the height of the heel, and is the same height as the heel to be built.

A projection 66 extends rearwardly from the base 18 of the mold and supports a pivot 68 for the rear end of a swinging arm 70. A presser member 72 is carried in the front end of the arm 70. The stem of the presser member 72 is screw-threaded, and is received in a correspondingly screw-threaded portion of the arm for the purpose of permitting adjustment of the presser member within the arm. The screw threads are slotted longitudinally of the stem, as shown at 74, at angular intervals of 90°. A locking member 76 is pivoted at 78 in the forward end of the arm 70 and has a finger hole 80 for the convenience of the operative in swinging the locking member about its pivot. When said member occupies the position shown in Fig. 2, its rear end lies in one of the slots 74 thus locking the presser member 72 against rotation, or in other words, securing it in adjusted position. When the locking member 76 is swinging into its alternative position it leaves the slot 74, thus permitting adjustment of the presser member as desired.

An upwardly extending guide member 82 forms the front end of the arm 70. A measuring slide 84 is mounted to slide up and down in the said guide member. A coiled spring 86 surrounding a sliding rod 88 tends to hold the measuring slide in its lowermost position. A measuring finger 88 adjustably held in the lower end of the measuring slide 84 by a set screw 90, is adapted to engage with the upper surface of the breast member 60 when the arm 70 is swung downwardly.

For the purpose of swinging the arm 70, a connecting rod 92 is pivoted at its forward end to said arm 94. The rear end of the connecting rod is free to slide through a block 96 carried by the swinging arm 12. A spring 98 is interposed between the block 96 and the arm 70 thus forming a yielding connection between the arm 12 and the arm 70. It will be obvious that as the arm 12 is swung forwardly, the arm 70 will be swung forwardly and downwardly until the presser member 72 engages the pile of heel lifts in the mold, when the arm 70 will stop, the yielding connection above described per-

mitting further forward movement of the arm 12.

Connected to the arm 12 is a link 100 having an abutment 102, which, as the arm is 5 swung forward, engages the arm 104 of a bell crank lever. The arm 106 of the bell crank lever carries the stop member 108 for controlling the operation of an ordinary starting and stopping mechanism comprising a Horton clutch 110 through which power is transmitted to the machine. From what has been already described it will be apparent that the starting is effected by swinging the arm 12 forwardly.

15 Mounted in an upper portion of the guide member 82 is a pin 112 adapted to register with a recess 114 in the measuring slide 84. The pin 112 is normally held out of said recess by a spring 116, and is in a position to 20 be engaged by the front face 120 of the arm 12 as the latter is swung forwardly. The construction of the starting mechanism is such as to require that the arm 12 be swung forwardly far enough to move the pin 112 25 into the recess 114 before the machine is started.

The downward swing of the arm 70 is obviously determined by the height of the pile of heel lifts in the mold, while the 30 movement of the measuring finger 88 of the measuring slide 84 is determined by the height of the breast member 60. If the height of the heel being built is not correct according to the gage 60, the relative movement 35 between the slide 84 and the guideway 82 will be such that the pin 112 and the recess 114 will not register, and the pin therefore can not enter the recess; this, of course, will only occur when the heel is of 40 improper height, and under such circumstances the pin 112 will prevent the arm 12 from being swung forwardly far enough to start the machine. The recess 114 is preferably elongated sufficiently to allow a 45 slight variation in the heights of heels, perhaps one-sixteenth of an inch.

While being swung forwardly the arm 12 is held up by a roll 122 riding upon the upper side of a stiff spring 124, but after 50 the starting of the machine the said arm is depressed through the action of the lever 15 which is actuated by a cam 126 upon the main drive shaft 128, thus applying pressure to the heel through the presser member 55 72 while a nail or nails are being driven through the heel to secure the lifts together by drivers 130 actuated from the main shaft 128 through a cam 132, a connecting link 134 and toggle 136.

60 The breast gage 60 is stationary and rigid. In order to permit downward movement of the presser 72, after the power mechanism has been started, to apply pressure to the heel, the following construction 65 is employed. The recess 114 is formed in a

block 138 guided to slide vertically in the slide 84. The block 138 is normally held in its uppermost position, against a stop 140, by a spring 142, see Figs. 2 and 5. After the pin 112 has entered the recess 114 the 70 spring 142 will permit the block 138 to yield downwardly as the member 82 and the presser 72 carried thereby are depressed to exert pressure upon the work.

The nature and scope of the present invention having been indicated, and an embodiment of the invention in its preferred form having been specifically described, what is claimed is:—

1. In a heel building machine, a mold 80 comprising a pair of heel engaging jaws mounted for movement in curved paths about centers located on opposite sides of the mold from their respective jaws and cam means for moving the jaws in said 85 curved paths.

2. In a heel building machine, a mold comprising a pair of jaws for engaging the sides of the heel mounted for movement about fixed centers forward and toward 90 each other in curved paths and cam means for effecting such movement.

3. In a heel building machine, the combination of pivotally mounted, crossed arms interconnected for equal and opposite movement, heel engaging jaws upon said arms, a cam roll connected to one of said arms, and a cam engaging said cam roll to actuate the 95 jaws.

4. In a machine of the class described, the 100 combination of means for exerting pressure upon the work, said means including a presser and a member mounted to swing into actuating engagement with said presser; and means for preventing movement of said 105 member into actuating position when the work does not conform to a predetermined standard of thickness.

5. In a machine of the class described, the 110 combination of means for exerting pressure upon the work, said means including a presser and a power actuated member movable into and out of actuating engagement with said presser; and means for preventing operation of said power actuated member 115 when the work does not conform to a predetermined standard of thickness.

6. In a heel building machine, the combination of a heel mold, means for securing together a pile of heel lifts placed in said 120 mold, heel measuring devices, and means for preventing operation of the securing means when the pile of heel lifts is not of proper height.

7. In a heel building machine, the combination of a mold, a presser foot for exerting pressure upon work in the mold, a driving shaft from which power is transmitted to said presser foot, starting mechanism, a measuring slide, and means coöperating 125 130

therewith to prevent operation of the starting mechanism when the work is not of proper thickness.

8. In a heel building machine, the combination of a mold including a breast gage, a presser for exerting pressure upon a heel in said mold, a measuring slide having a portion adapted for engagement with said breast gage, and means for preventing activation of said presser except when the heel

is of substantially the same height as the breast gage.

In testimony whereof I have signed my name to this specification in the presence of two subscribing witnesses.

JOHN H. RICHARDSON.
